LOCKING BAR ACTUATING MECHANISM

George H. Jones and Peer D. Nielsen, Lorain,
Ohio, assignors to National Tube Company, a
corporation of New Jersey

Application August 3, 1940, Serial No. 350,606

2 Claims. (Cl. 214—26)

This invention relates to improvements in lock rod operating devices used on machines for handling the charging boxes in the charging of scrap ore or other materials in melting furnaces such as open hearth furnaces or the like. Such charging boxes are filled with materials and engaged in sequence by the charging machines, locked in position, then lifted and advanced into the furnace. Rotation of the box discharges the contents thereof, whereupon it is withdrawn from the furnace and deposited on a car or other support and disengaged from the charging machine. The operation may then be repeated in connection with other charging boxes. The locking rod, in accordance with the present invention, may be either manually or power-operated, and it is effective for preventing the box from becoming disengaged from the ram of the charging machine during the operation.

In practice, it is necessary that positive and reliable means be employed to advance the locking rod into position, to hold it securely in place for the desired interval, and permit its ready withdrawal when it is desired to disengage the ram in the charging box.

Heretofore both manually and mechanically operated devices have been used for actuating charging machine locking bars, but these known devices, particularly those which are mechanically operated, are complicated, expensive to manufacture and maintain, and in some cases have been found to be unreliable.

The present invention aims to provide a relatively simple locking bar actuating device which lends itself equally well to either manual or power operation. The features of the invention will be fully apparent from the following detailed disclosure when read in connection with the accompanying drawing, and will be defined with particularity in the appended claims.

In the drawing,

Figure 1 is a somewhat diagrammatic side elevation of a charging machine mounted in juxtaposition to an open hearth furnace, the charging machine being provided with an improved locking rod operating device embodying the present invention.

Figure 2 is a skeletonized view showing portions of the charging machine and its relation to the locking rod operating mechanism of the present invention.

Figure 3 is an enlarged detail of the right-hand portion of Figure 2, showing in detail the improved features of the locking rod operating mechanism.

Referring in detail to the drawing, F is a conventional representation of an open hearth furnace which is to be charged by a charging machine embodying the operating device of the present invention. The charging machine, indicated as a whole at M, rides on tracks T which extend longitudinally in front of several furnaces. As illustrated, the machine is adapted to sequentially engage charging boxes B, enter them into the furnace, dump the contents thereof, withdraw, and deposit them on a suitable car C traveling on tracks directly in front of the furnaces.

The present invention is directed particularly to an improved arrangement of coacting instrumentalities for easily and quickly disengaging the locking rod 1, best shown in Figure 2, from the charging box B, this locking rod being arranged to be actuated either by power means or by manual effort. The change from manual to power operation can be made by the simple insertion or removal of certain connecting pins, as will hereinafter more fully appear.

At its rear extremity the locking bar engages a ball-joint 2 journaled in a split crosshead 3 which slidably engages an arcuate slot 4 formed in a depending arm 5 pivotally supported on a pin 6 carried by a bracket mounted on a carriage R which is movable toward and from the furnace on suitable guide tracks supported by the charging machine M.

Near its lower end, the arm 5 is pivotally connected by means of a link 7 with the arm 8 of a bell crank which is connected by means of a link 35 9 with the core 10 of a double acting solenoid 11 mounted on a suitable bracket which moves toward and from the furnace with the carriage R. A removable pin 12 provides means whereby the locking rod can be actuated either by the power of the solenoid or by manual means to be presently described. The bell crank 8 is mounted on a rock shaft 8a to which is secured a lever 13 adapted to be selectively connected, by means of a removable pin 14, with a connecting rod 15 whose lower end is connected by a pin 15a with a manually operable lever 16 carried by shaft 16a suitably journaled in bearings mounted on the carriage R.

When the locking rod 1 is to be operated manually, the pin 12 is removed, thus disconnecting the link 9 and solenoid 11 and permitting the motion of the hand lever 16 to be transmitted to the locking bar through the connecting rod 15, lever 13, rock shaft 8a, bell crank arm 8, link 7, arm 5, crosshead 3, and ball-joint 2. When

the locking rod is to be operated by the power means, the pin 12 is inserted, and at this time the hand lever 16 and rod 15 are rendered ineffective by removal of the pin 14. In the event of failure of the solenoid 11 to properly operate, manual operation of the locking rod can be quickly and easily resumed upon replacement of the pin 14 and removal of the pin 12, as will be understood.

To lock the ram 18 in the charging box B, the lever 16 is pushed forward to the position shown in Figures 2 and 3. This causes rod 15 to move to the right, thus moving lever 13 in a clockwise direction about its shaft, which causes link 7 to move the arm 5 in a clockwise direction about the pivot pin 6, thereby advancing the locking bar 1 through the ram 18 and spindle 23 into the socket formed in the head of the charging box B. Retraction of the locking bar is accomplished manually by reversal of the above movements. The power operation of the bar, it will be understood, is effected by the solenoid transmitting motion through the parts 9, 12 and 8, instead of the parts 16, 15 and 13.

The ram and spindle of the charging machine, in accordance with usual practice, are arranged for rotation about their common longitudinal axis, to permit the charging box to be rotated and dumped into the furnace. As is also customary, the spindle is mounted on a trunnion 20 and is adapted to be rocked through a small arc by means of a crank 21 and pitman 22 which is pivotally connected at 22^a to the spindle-supporting frame 24. Because the parts are mounted for pivotal movement about the trunnion 20, it is necessary that the locking bar and its actuating mechanism be arranged to compensate for such movement. Rotation of the locking bar 1 with the ram is permitted, since the ball-joint 2 can turn freely in the crosshead 3. Vertical movement of the bar is made possible without disturbing the position of the operating levers and rods by the novel design of the arm 5 in which the crosshead 3 is free to move in the slot 4. This slot is arcuate, and the radius thereof is struck from the pivotal axis of the trunnion 20. With the parts thus constructed and arranged and the locking bar in locked position, the ram can assume any position within its own limits without imparting any longitudinal movement 50 to the locking bar. With the locking bar withdrawn from locked position, it can move slightly, but the movement is of such small magnitude that it is of no consequence. However, a compensating slot 17 may be provided in the connecting rod 7 to eliminate the transmittal of this movement to the hand lever 16. Such arrangement is distinguished from prior conventional charging machines wherein the hand lever oscillates over a wide arc as the ram is rocked about the trunnion 20 and thus endangers the safety 60 of the charging machine operator. Such objectionable movement of the hand lever with relation to the operator's platform in the prior conventional locking bar arrangement is brought about by the fact that the elevation of the operator's platform is constant to the relation of the floor, whereas the lock bar moves up and down with the ram. Since the ram-actuating mechanism is usually so connected in the conventional system that all parts must move with the ram, there has been no alternative but to allow the hand lever to swing through a considerable arc 65 as the ram is shifted. This objectionable feature is eliminated in the device of the present 70 75

invention by the provision of the ball-joint and crosshead operating in the arcuate slot of the arm 5, as herein disclosed. In most mechanically operated locking bars with which we are familiar, the operating mechanism is arranged so that it travels with the ram and is connected with the operator's platform solely by electrical means. In the novel arrangement herein disclosed, it is possible to mount the source of power on the carriage upon which the operator's platform is supported, as relative motion between the locking bar and the solenoid or hand lever is compensated for by the slotted arm 5. Such location of the operator's platform is advantageous in that the parts are thus made readily accessible for inspection and repair. It is also to be noted that the arrangement of the ball-joint in the inner end of the locking bar permits the latter to rotate freely with the ram and the charging box, so that wear at the outer end of the locking bar is held to a minimum.

The parts constructed and arranged as hereinbefore described are superior to prior art devices for the following reasons: both the manual and mechanical operating mechanisms are simpler than any equipment on the market; the operation can be changed from manual to mechanical or vice versa by simple means; the movement of ram and locking bar through vertical arc is not transmitted beyond arm 5 to operating rods and levers; hazardous oscillation of hand lever at operating platform is eliminated; the locking bar is free to rotate with ram and charging box, thus eliminating wear on the end of the rod and in the charging box head socket; longitudinal movement of locking rod with respect to associated parts cannot occur except when initiated by operation of solenoid 11 or hand lever 16; and the simplicity of our novel design effects important savings in the cost of manufacture and maintenance.

The power operation through solenoid, levers and segmental arm is much less complicated than any other mechanically operated devices heretofore available so far as we are aware.

The mounting of the solenoid or other source of mechanical power on the carriage instead of on the moving ram parts is an improvement over other known designs.

While we have described quite specifically the embodiment of the invention herein illustrated, it is to be understood that various modifications may be made by those skilled in the art without departing from the invention as defined in the appended claims.

We claim:

1. A charging machine of the character described, having a carriage thereon movable toward and from a furnace to be charged, a ram for handling charging boxes, trunnion means pivotally supporting the ram from said carriage to permit limited angular movement of the ram, a locking rod extending through the ram for securing the box to one end thereof, and means at the opposite end of the ram for actuating the rod including an arm pivotally mounted on the carriage, a slide connection between the arm and rod whereby the ram may be rocked without lifting or lowering said arm, and means mounted on said carriage operatively connected with said arm and effective to rock it to impart movement to said locking rod through said slide connection.

2. A charging machine of the character described, having a carriage thereon movable toward and from a furnace to be charged, a ram

for handling charging boxes, trunnion means pivotally supporting the ram from said carriage to permit limited angular movement of the ram, a locking rod extending through the ram for securing the box to one end thereof, means at the opposite end of the ram for actuating the rod including an arm pivotally mounted on the carriage and having a slot formed therein, a mem-

ber slideable in said slot having a ball and socket connection with the locking rod, and operating means mounted on said carriage and connected with said arm for imparting locking and releasing movements to said rod.

GEORGE H. JONES.
